UNITED STATES PATENT OFFICE.

WILLIE R. D. ALLEN, OF HARDMAN, OREGON.

VEHICLE-SEAT SPRING.

SPECIFICATION forming part of Letters Patent No. 292,151, dated January 22, 1884.

Application filed September 18, 1883. (No model.)

To all whom it may concern:

Be it known that I, WILLIE R. D. ALLEN, a citizen of the United States, residing at Hardman, in the county of Umatilla and State of Oregon, have invented certain new and useful Improvements in Vehicle-Seat Springs; and I do hereby declare the following to be a full, clear, and exact description of the invention, such as will enable others skilled in the art to which it appertains to make and use the same.

This invention relates to certain improvements in vehicle-seat springs; and it has for its object to provide means to prevent such seats from becoming loose upon their supporting-springs, so as to avoid lateral swaying; and with this end in view the invention consists in securing an angular brace or braces to the seat itself and to the lower leaves of the springs, the latter connection being yielding, as will hereinafter more fully appear.

In the accompanying drawings, forming a part of this specification, and on which like reference-letters indicate corresponding features, Figure 1 is a front elevation of a vehicle-seat mounted upon springs and provided with my improved braces; and Fig. 2, a vertical cross-sectional view of the seat, showing my brace in side elevation.

The letter A indicates the vehicle-seat, the same being constructed of any approved material and of any desired shape or size, and mounted upon and secured to elliptical springs B in the usual manner. The lower halves of the springs are secured to strips C, which in turn are secured to the vehicle-body; or they may be fastened directly to such body themselves.

It is also to be observed that I do not confine myself to any particular form of spring,

since it is obvious that my braces, to be presently described, may be applied to seats having spiral springs as well.

The letter D designates the braces, preferably of metal, the respective ends of which are secured to the seat and the upper half of the springs. From the seat they extend obliquely or outwardly to a point just below the lower half of the springs; thence they extend vertically to the upper half thereof, where, as above stated, they are fastened, the said vertical portions passing through eyes or clips E, connected rigidly to the lower portions of the springs. These clips serve to form a connection between the braces and the said portions of the springs. By this means it will be observed that the vertical play or reciprocation of the seat is left perfectly free, while at the same time all lateral swaying is entirely avoided, my invention being particularly designed for use in uneven rocky countries.

These braces may also be applied with advantage to the bodies of vehicles, as well as to the seats thereof.

Having thus fully described my invention, what I claim as new, and desire to secure by Letters Patent, is—

In a vehicle-seat, the combination of the braces secured thereto at one end, extending obliquely and downwardly, and then vertically, with the springs having clips which receive said braces, and having their upper portions rigidly secured thereto, substantially as described.

In testimony whereof I affix my signature in presence of two witnesses.

WILLIE R. D. ALLEN.
